PLUG-IN DEVICE AND SOCKET RECEPTACLE

Hugh H. Eby, Jenkintown, Pa.

Original application May 6, 1938, Serial No. 206,457. Divided and this application December 18, 1940, Serial No. 370,642.

4 Claims. (Cl. 173—328)

This invention relates to plug-in devices and socket receptacles therefor, constituting a division of my application filed May 6, 1938, Serial No. 206,457, now Patent 2,290,172.

With the advent of the present type of "octal" tubes the use of a separate indexing prong or guide member as a means for aligning contact prongs with appropriate socket receptacle contacts, was introduced into the commercial art of plug-in devices. As provided hitherto, however, the aligning or angular position determinator took the form of a substantial cylinder having an external rib disposed longitudinally on the cylinder, requiring a complementally shaped guide aperture in the receptacle. This is shown for instance in the patent of Shrader No. 2,080,837 dated May 18, 1937, and necessitated termination of the rib short of the truly cylindrical lower end of the guide member so that rotation thereon was provided for. With such guide member disposition, concentric to a circular series of prong contacts, it will be evident that a relatively large area in the center of the plug-in device is incapable of containing contact prongs. This area lies within the circle containing the first mentioned series of prongs.

In my co-pending application, Serial No. 25,055, filed June 5, 1935 now matured into Patent No. 2,196,697, I have disclosed a socket receptacle arranged to receive the present day "octal" type tube or allied analogous devices, in which a form of housing and guide for the guide member or prong is disclosed and in which an eyelet is used as the central guide member receiving guide element whereby certain important advantages are secured which advantages will also attach to the instant invention, as will later appear, together with new advantages present in this instant improvement on the invention of said application.

It is among the objects of the invention; to provide improvements in plug-in devices; to provide an improved socket receptacle for plug-in devices; to overcome the disadvantages of the prior art in plug-in devices and socket receptacles for plug-in devices; to provide improvements in contacts for plug-in devices; to provide improvements in contacts for socket receptacles; to provide complemental plug-in devices and socket receptacles therefor, both of which are possessed of highly advantageous and efficient characteristics; to improve indexing characteristics of guided plug-in devices; to provide an improved combination guide and contact element in the socket receptacle in which an indexing prong or guide member is slidably inserted to interlocked engage-

ment and in which the plates of the socket receptacle are strengthened, rendered susceptible to extreme thinness, and the plates are held rigidly together to secure and maintain permanent registration of all contact apertures with an elimination of the eyelets or the like normally necessary hitherto, and which precludes relative rotation of the plates of the receptacle; to provide a complemental plug-in and socket assembly in which the disposition of the guide prong or member and its guiding receptacle element is such that the male guiding element is universal as regards its guided reception in both the present day "octal" receptacle and that of the instant invention, while the female guiding receptor is selective to receive only the guiding member of the instant invention; to provide a combination contact with anchoring means such as to accord with variations in the thickness of the plates of the socket receptacles, to provide means for locking plug-in devices to socket receptacles, and many other objects and advantages will become more apparent as the description proceeds.

In the accompanying drawing forming part of this description,

Fig. 1 represents a perspective of an illustrative embodiment of a locking guiding female contact.

Fig. 2 represents a plan of a socket assembly with the contact of Fig. 1 in operative guiding position substantially concentrically of the socket.

Fig. 3 represents a fragmentary section, partially in elevation of the plug-in end of a plug-in device, showing the cooperative guiding aligning member for association with the contact of Fig. 1.

Fig. 4 represents a fragmentary plan on an exaggerated scale of the guiding contact of Fig. 2, showing in dotted lines the outline of a conventional present day type of "octal" substantially cylindrical guide element, to indicate that it cannot enter the guiding contact.

Fig. 5 represents a transverse section on line 5—5 of Fig. 3, through the centering indexing guide member to show the association of the metallic contact element with the molded non-metallic prong.

Fig. 5-a represents a similar transverse section through a modified form of guiding member.

Fig. 6 represents a similar section, taken on line 6—6 of Fig. 3, to show the locking grooves disposed therein.

Fig. 7 represents a fragmentary plan, partially in section, of a conventional present day type of "octal" tube-receiving socket guide element of the substantially cylindrical type, having a guide

groove longitudinally in one surface, with the guide prong of Fig. 3 in section and disposed guidingly in the element, to show the adaptability of the angular guide element to present sockets.

Fig. 8 represent a plan of the end of the plug-in device of Fig. 3.

Fig. 9 represents a fragmentary side elevation of an assembled plug-in device and socket, showing the locking interengagement of the guiding device and contact.

Referring to Fig. 1, there is disclosed an illustrative embodiment of a female contact, illustrated as a substantially triangular contact having a backing portion 10, side arms 11 and 12, each of which has an integral flange or longitudinal extension, respectively 13, 14 and 15, arranged to overlie, or be peined over upon, the top plate or lamination 16, of the socket receptacle having a lower plate 17. The plates are shown in assembly in Fig. 9. The socket plates 16 and 17, have registering triangular apertures, illustratively centrally disposed and are surrounded by the registering prong and contact apertures 18 in any suitable or desired number as to receive the contact prongs 28 of the male member 39 as shown in Fig. 3, and in which female contacts of any desired construction are mounted as at 19 as shown in Fig. 9. Obviously the male member may be any desired plug-in device, and illustratively only, will be considered as a radio tube. The registering triangular apertures receive in plates 16 and 17 of the base, with a slight lateral clearance, the combination female contact member of Fig. 1. The respective flanges 13, 14 and 15, of the contact are formed of predetermined length variable in overlap on the upper plate to accord with a predetermined thickness condition of the laminations, and are initially coextensive with the contact surfaces of which they are extensions. After the contact is disposed in the registering apertures, the flanges are peined over or otherwise upset to engage the upper surface of the base. With small variations in thickness of the laminations the flanges 13, etc. will have longer or shorter portions extending over the top plate or receptacle base according to requirements at the time of upsetting, as will be clear, and as is indicated by the dotted line extensions in the fragmentary plan of Fig. 4. The under surface of the lower plate or lamination 17 will be engaged by a suitable stop carried on the contact member, such as flanges, dimples, tongues, ribs or the like, but as shown in Fig. 1 the stop comprises tongues or ears 20', which may but need not be resilient. With the contact inserted axially from the bottom until the ears 20' in the side walls, and in the backing wall as well, if desired, engage abuttingly the lower surface of the plate 17, the upsetting of the terminal flanges or lips of the upper end against the upper surface of the plate 16 will firmly lock the two plates together, with all of the advantages disclosed in my said earlier filed application 25,055, now matured into Patent #2,196,697 of which this is in some characteristics at least, an improvement, with certain added advantages as well, even without the locking and electrical contact features to be described.

Thus, as indicated in Fig. 4, the substantially triangular contact is so proportioned that the present type of "octal" plug-in device having a central substantially cylindrical selector or indexor with a longitudinal rib, on part of the selector, as indicated in dotted lines in said Fig.

4, obviously can't enter the guide contact under discussion.

The contact of Fig. 1 is arranged as a locking device, and illustratively this is accomplished by turning in all, or all but the extreme marginal portions of the lower edge surfaces of the side arms 11 and 12, as at 21 and 22, for an operative association that will be discussed. The contact is completed by the terminal extension of tail 23. Where no contact functioning is desired, the tail may be omitted to considerable advantage in economy.

The male plug-in device for association with the socket just described, comprising a base 39, may be conventional as to contact element prongs 28, but is provided with a central angular indexor or guide member, selector, 24, which is of such contour as to guidingly engage in the angular or triangular female contact member of Fig. 1, and may be, and in the preferred form is provided with a metallic element 25, as an electrical conductor, making the guiding device 24 a contact element, or the guide member 24 may be all of moldable material or all of metal. This element 25 may be suitable disposed as in the disclosures of Figs. 5 and 6, in the apex, or as shown in Fig. 5-a, in a side wall, just so that electrical contact can be established therewith. Obviously the female contact may be grooved or otherwise formed as to facilitate electrical engagement with any form of male electrical contact guide member. The molded extension 24 has relatively divergent side walls 26 and 27 arranged to slidably engage the side arms 11 and 12 and each, preferably, is provided with a transverse lateral groove as at 28 and 29, respectively above the lower tapered or curved guiding end 23 of the indexor 24, in such position as to receive and be grippingly engaged by the turned lips 21 and 22, of the female contact respectively, to anchor the male and female members together, and thus to hold the plug-in device from casual or accidental withdrawal from the socket as shown in Fig. 9.

The selector 24 of the plug-in device is interestingly proportioned in that, as shown in Fig. 7, on an enlarged scale, the guide prong or selector 24 in addition to entering the contact of Fig. 1, can also enter and be guided into proper angular positioning in the conventional socket guiding apertures of the present type of "octal" tubes. Thus the substantially cylindrical guide member 24 having the longitudinal external recess 32 communicating therewith, to receive the guide member of present "octal" type of tubes, will receive the guide prong 24, with the apex 23 thereof slidably guided in said guide recess 32, as will be clear. Although in one dimension the angular guide member 24 is fairly large yet transversely it is less than the diameter of the guide recess 32. It has already been mentioned that the reverse of such guided insertion is not true, in that the substantially cylindrical guide cannot enter the substantially triangular socket of this invention. The creation of a restricted type of plug-in device and receptacle by the invention herein will be evident.

The manifold advantages and economical construction of the invention will be obvious, as will the fact that many other modifications will occur to those skilled in the art, and it is desired that all such shall be construed as within the scope of the invention unless otherwise expressly limited in the appended claims.

Having thus described my invention, I claim:

1. In socket receptacles, a metallic guiding element arranged to guidingly receive a projecting guide element on a plug-in device, comprising a backing portion and a pair of side arms angularly divergent therefrom, flanges mounted on one end of the metallic device arranged for distortion to anchor the guiding element in an insulating base, supplemental anchoring means on said element spaced from the flanges and adapted to engage said base, and an inturned edge formed on said metallic element spaced from the plates arranged to engage and interlock with the projecting guide element on a plug-in device.

2. In socket receptacles, a base, female contacts mounted on the base, a female triangular contact of generally isosceles form mounted on the base and having a predetermined angular relation to said first mentioned contacts arranged to guidingly receive a projecting substantially triangular contact-making guide element on a plug-in device of cooperatively generally isosceles form having a recessed portion in one single predetermined angular relation of the socket and plug-in device, said female triangular contact comprising a backing portion and a pair of side arms angularly divergent therefrom, means integral with the triangular contact to anchor same to the base and means on said side arms to lockingly engage the recessed portion of such guide element on a 30 plug-in device after insertion of said guide element into said female triangular contact.

3. In socket receptacles, a base, female contacts mounted on the base, a female triangular contact of generally isosceles form mounted on the base and having a predetermined angular relation to said first mentioned contacts arranged to guidingly receive a projecting substantially triangular contact-making guide element on a plug-in device of cooperatively generally isosceles form having a recessed portion in one single predetermined angular relation of the socket and plug-in device, said female triangular contact comprising a backing portion and a pair of side arms angularly divergent therefrom, means comprising a lower marginal inturned edge of a side arm integral with the triangular contact to anchor same to a base and means on said side arms to lockingly engage the recessed portion of such guide element on a plug-in device after insertion of said guide element into said female triangular contact, and a soldering terminal integral with said backing portion.

4. In combination, a plug-in device having a substantially triangular guide element having a lateral recess in one surface thereof transverse 25 of the guide element, a guiding element comprising a backing portion and side arms defining a substantially triangular channel, the edges of an arm being inturned transverse of the guiding element to engage in said recess.

HUGH H. EBY.
